James Hulchinson, of Lansingburgh, N.Y.
Assignor to
J. C. Whipple & Stephen C. Haskell, of Lansingburgh, N.Y.
Letters Patent No 875 Dated Mar. 10th 1837.

The Schedule referred to in these Letters Patent and making
part of the same.

To all whom it may concern:

Be it known that A. James Hutchinson,
of Lansingburgh, in the County of Rensselaer, and State of
New York, have invented or produced a new design or figure,
to be printed or stamped upon floor Cloths, and I do hereby
declare that the following is a full and exact description of
the same viz:

The pattern is composed of various geometrical figures
formed by bands or lines of different shades of color. The two principal
figures viz: the octagon and Diamond are ornamented in their
centres by figures placed in a tessellated or inlaid style in dif-
ferent colors: so as to give the objects the appearance of being
raised above the surrounding grounds upon which they are
placed: the general arrangement and details of the pattern
being shown by the annexed copy or drawing which forms
a part of this specification.

And what is claimed as my inven-
tion and desired to be secured by Letters Patent of the United
States is the arrangement of ornamental figures forming a
design for Floor Cloths as shown in the aforesaid draw-
ing.
